UNITED STATES PATENT OFFICE.

THOMAS W. COOPER, OF BUCKHEAD, GEORGIA.

STEAM-HEATING SYSTEM.

1,079,637.

Specification of Letters Patent.

Patented Nov. 25, 1913.

Application filed June 3, 1913. Serial No. 771,527.

To all whom it may concern:

Be it known that I, THOMAS W. COOPER, a citizen of the United States, residing at Buckhead, in the county of Morgan and State of Georgia, have invented certain new and useful Improvements in Steam-Heating Systems; and I do hereby declare the following to be a full, clear, and exact description of the invention, such as will 5 enable others skilled in the art to which it appertains to make and use the same.

This invention relates broadly to locomotive boilers, and has particular reference to that type of systems employed in connection 15 with locomotives for heating the feed water prior to its entrance into the boiler.

As its principal object, this invention contemplates the provision of means for utilizing a portion of the exhaust from the steam chest of the locomotive for partially heating 20 the feed water for the locomotive, before it enters the boiler.

A further object is to simplify the construction of devices of this general character 25 to such an extent that they may be cheaply manufactured, and durable and efficient in their operation.

A still further object is to construct this invention with such regard as to proportion, 30 number and arrangement of parts that it may be readily and conveniently applied to any locomotive of standard type without necessitating the alteration or disassembling of any of the parts of the locomotive.

35 A further object is to provide means for drawing the feed water into the lead pipes to the boiler at that point of the water tank which is of the highest temperature.

A yet further object is to provide means 40 for utilizing the water condensation, of the exhaust steam employed in heating the feed water, by reconducting it to the boiler after it has accomplished the heating of the feed water.

45 The above and additional objects are accomplished by such means as are illustrated in the accompanying drawings, described in the following specification, and then more particularly pointed out in the claims which 50 are appended hereto and form a part of this application.

With reference to the drawings, wherein I have illustrated the preferred embodiment 55 of my invention as it is reduced to practice, and throughout the several views of which similar reference numerals designate corre-

sponding parts: Figure 1 is a side elevation with several of the side plates broken away to more clearly disclose the assembled relation of the various parts of this invention. Fig. 2 is a top plan view of the locomotive. Fig. 3 is a side elevation of the tender with a portion of the side broken away to clearly illustrate the arrangement of the heater; and Fig. 4 is a top plan view of the tender with the invention in assembled position therein.

This invention consists essentially in two main elements, the pipes for conducting the exhaust steam from the steam chest, to the tender water tank and for reconducting the heated feed water back to the boiler, and the heater employed in utilizing the exhaust steam for heating the feed water. Taking up these elements in the order named, there 70 has been provided a pair of cylindrical casings 1 and 2 arranged on each side of the locomotive and preferably at the lower part thereof. Leading into each of the casings from the exhaust pipe of the steam chests 80 3 and 4 are a pair of steam pipes 5 and 6. The pipe 6 is directed through the casing 2 to its far end, and is then returned to the forward end as illustrated in Fig. 1, and directed to the exhaust stack, as at 7 in Fig. 85 1. The pipe 5 is arranged within the casing 1 in a similar manner having its lower terminal in communication with the exhaust stack as at 8 in Fig. 2. The pipe 5, however, is tapped as at 9 by a pipe 10 which leads 90 rearwardly into the water tank 11 of the tender, as illustrated in Fig. 3, and is adapted to conduct a portion of the exhaust steam through a heating coil 12 arranged in a preferably cylindrical closed casing 13, 95 which may be mounted in the tank 11 of the tender in any desired manner. Communicant with the casing 13 and at the upper portion thereof, as at 14, is a water pipe 15, provided to conduct the water 100 forced into the casing, in a manner to be hereinafter described, into the boiler 16 of the locomotive. This pipe 15 is passed through the entire length of the casing 1, is then directed, as at 17, through the fire 105 tubes of the locomotive, thence through the fire box, as at 18, and subsequently through the casing 2, as at 19, from which it leads into the boiler 16, as indicated at 20. A force pump 21 is arranged within the tender 110 tank 11 and is designed to force the water from the tank into the casing 13, and at the

lower portion thereof. A similar force pump 22 is mounted in the engine cab and is attached to the pipe 15 to force the water into the locomotive boiler 16.

5 The actual construction being thus disclosed, it now remains to describe the operation and to enumerate the many advantages resulting from the novel form of structure of this device.

10 Briefly, the operation is as follows: The steam exhaust from the cylinder 4 is conducted by the pipe 5 through the casing 1 and thence to the atmosphere through the stack, as at 8. As above described, a portion 15 of the steam is shunted through the pipe 10, and passed through the water tank 11 into the casing 13 and then finds its way through the coil heating pipe 12 to the top of the casing 13 as at 23, where it impinges 20 against the casing and condenses, mingling with the water forced from the tank 11 into the casing 13 by the pump 21. The pump 22 acts to draw the water thus heated within the casing through the pipe 15, which, being 25 communicant with the upper portion of the casing 13 draws off the hottest water in the casing. It will be apparent from the above disclosures that the feed water conducted through the pipe 15 is subjected to four 30 super-heating elements, being first passed through the steam heating cylinder 1, thence through the fire tubes of the locomotive, subsequently through the fire box and finally through the steam heated cylinder 2 from 35 which it issues into the locomotive boiler 16. In this manner, the temperature of the feed water is raised to the highest possible degree of heat obtainable by employing the exhaust steam as a heating means.

40 It is desirable to emphasize the fact that inasmuch as this invention consists so far as an apparatus employed is concerned, in mechanical structures which are in themselves neither new nor novel, it rather makes 45 claim to display of invention because of the novel and efficient arrangement of the various mechanical means employed.

In reduction to practice, I have found that the form of my invention, illustrated 50 in the drawings and referred to in the above description, as the preferred embodiment, is the most efficient and practical; yet realizing that the conditions concurrent with the adoption of my device will necessarily vary, 55 I desire to emphasize the fact that various minor changes in details of construction,

proportion and arrangement of parts may be resorted to, when required, without sacrificing any of the advantages of my invention, as defined in the appended claims. 60

What is claimed is:

1. The combination with a boiler, smoke stack, fire box and feed tank of a locomotive steam engine, of a coil radiator mounted in the feed tank, a sealed casing for said radiator, a force pump mounted within said feed tank and connected with the lower terminal of said sealed tank, a cylindrical casing arranged on each side of said locomotive, a steam pipe of each cylindrical casing 65 connected at one terminal with the exhaust pipe of the steam chest and at its other terminal with the smoke stack, said pipe coiled within said cylindrical casings, a second steam pipe connected with one of said first 70 steam pipes within one of said cylindrical casings at one terminal and at its other terminal to the lower coil of said coil radiator, a water pipe connected at one terminal with the upper portion of said sealed casing and 75 at its other terminal with said boiler, said water pipe directed through one of said cylindrical casings, the fire tubes of said locomotive, the fire box and finally through the other of said cylindrical casings and into 80 said boiler and a force pump adapted to force the water from said feed tank through said water pipe.

2. The combination with a boiler, smoke stack, fire box and feed tank of a locomotive 90 steam engine, of heating means mounted within said feed tank, cylindrical casings secured to said boiler, pipes connected with the steam chest of the locomotive, coiled within each of said cylindrical casings and 95 terminating in upwardly extending portions communicant with the smoke stack, a pipe connected with one of said steam pipes and with said heating means, a heated water supply pipe connected with said heating means 100 and said boiler, said last named pipe directed through one of said cylindrical casings, the fire tubes, the fire box, into the other of said casings and finally into said boiler, and a plurality of pumps for circulating the water in said pipes. 105

In testimony whereof I affix my signature in presence of two witnesses.

THOMAS W. COOPER.
